UNITED STATES PATENT OFFICE

127,834

DESIGN FOR A MOTORBOAT CHAIN DRIVE HOUSING

Lloyd Smith Puckett, Seattle, Wash.

Application December 16, 1940, Serial No. 97,354

Term of patent 14 years

To all whom it may concern:

Be it known that I, Lloyd Smith Puckett, a citizen of the United States, residing at Seattle, in the county of King, State of Washington, have invented a new, original, and ornamental Design for a Motorboat Chain Drive Housing, of which the following is a specification, reference being had to the accompanying drawing, forming a part thereof, and in which

Fig. 1 is a side elevational view of a motor-boat chain drive housing showing my new design.

Fig. 2 a bottom plan view;

Fig. 3 a front elevational view; and

Fig 4 a partial top plan view.

I claim:

The ornamental design for a motorboat chain drive housing, as shown.

LLOYD SMITH PUCKETT.
